W. H. MUZZY.

FUEL FEEDING SYSTEM FOR AUTOMOBILES.

APPLICATION FILED DEC. 10, 1917.

1,314,971.

Patented Sept. 2, 1919.

UNITED STATES PATENT OFFICE.

WILLIAM H. MUZZY, OF CHICAGO, ILLINOIS, ASSIGNOR TO STEWART-WARNER SPEEDOMETER CORPORATION, OF CHICAGO, ILLINOIS, A CORPORATION OF VIRGINIA.

FUEL-FEEDING SYSTEM FOR AUTOMOBILES.

1,314,971.

Specification of Letters Patent.

Patented Sept. 2, 1919.

Application filed December 10, 1917. Serial No. 206,385.

To all whom it may concern:

Be it known that I, WILLIAM H. MUZZY, a citizen of the United States, residing at Chicago, in the county of Cook and State 5 of Illinois, have invented certain new and useful Improvements in Fuel-Feeding Systems for Automobiles, of which I declare the following to be a full, clear, and exact description.

10 This invention relates to improvements in fuel feeding systems for automobiles or the like and has more particular relation to improvements in devices of the character shown and described in my Patent No. 1,201,077 issued Oct. 10, 1916 and No. 1,222,235, issued April 10th, 1917 and my copending application 171,180, filed May 26, 1917 and reference is made to the above patents for any detail descriptions not contained in the following specifications.

25 One of the several objects of the invention is to provide improved means in vacuum systems of the type mentioned for causing intermittent pumping by the employment of 25 part of the liquid as a sealing trap for the air vent.

30 Another object of the invention is to provide an improved means for preventing the system overpumping and to arrest its pumping effectiveness when a certain level of the liquid is reached.

35 A further object of the invention is to prevent any overflow of the tank or loss of the fuel when a grade is descended that brings the main gasoline tank to a level above the top of the vacuum tank.

40 A further object is to provide improved devices for obstructing the flow of the liquid through the air vent and thus raise the vacuum in the vacuum or pumping chamber and prolong the pumping operation without obstructing the free passage of air through the vent after the sealing liquid has been exhausted.

45 Another object is to more completely break up the particles of gasoline that pass through the air vent and form a spray or mist in which the air is almost completely saturated with gasoline and in condition to be fed to the engine as a combustible mixture.

50 Another object is to provide means for priming the tank at any time without opening it in any way.

Another object is to provide means for

introducing hot air into the tank so as to assist in producing a more combustible mixture.

55 A further object of the invention is to provide improved means for quickening the action of the tank so that more pumping 60 operations will take place in a given period of time and a more uniform level of gasoline kept in the tank against any emergency such as high speed or a very steep grade when the throttle will be fully open and the effective 65 vacuum greatly reduced.

A still further object of the invention is to provide improved means for retaining in the tank sufficient gasoline to prime the trap and leave a surplus for the engine when 70 the engine stops from the exhaustion of the tank because of a drain beyond the capacity of the tank.

In carrying these and other objects of the 75 invention into effect I utilize certain constructions, combinations and arrangements of parts all of which will be hereinafter more particularly set forth and claimed.

In the accompanying drawings forming 80 part of this specification;

Figure 1 represents a central vertical section through a vacuum fuel feeding tank and connections embodying my invention,

Fig. 2 represents a detail front elevation of one of the flap valves, and

Fig. 3 represents a detail vertical section of a modified form of obstruction for the upper end of the air vent.

In general terms the invention may be said to operate by the vacuum created in the manifold of the engine of the machine and which is transferred to my tank to draw the gasoline from a relatively low main fuel supply at the rear of the machine in intermittent pumping operations as described 95 and shown in my aforesaid patents and reference is made to the same for any further description of this general operation desired. After being drawn into the elevated tank the gasoline is let down intermittently 100 into a lower compartment where it is held under atmospheric pressure and fed to the carburetor of the engine by gravity.

In the aforesaid drawings 1 represents the outer tank or shell, 2 the vacuum tank 105 or chamber, 3 the sealing cover of the same and 5 the air or vacuum connection for establishing communication between the tank

and the manifold of the engine in a manner well known in the art and shown and described in my aforesaid patents. The upper edge of the tank 1 is provided with an outwardly turned flange to which the inner tank 2 which is formed with a similar flange, is secured by screws 24 which pass through the flanges and screw into a ring 54 which in turn is secured to the upper part of the 10 tank 1. A cork packing ring 22 is interposed between the cover 3 and the flange of the tank 2 to secure an air tight joint.

The fitting 5 is provided with a reduced suction port 55 the size of which may be previously determined according to the displacement of the engine and the carburetor employed, to give the engine the most effective mixture for perfect operation at all times, the feed through the port 55 being constant. In order to prevent any raw gasoline from being drawn into the port 55 from the splash in the tank 2 a semi-cylindrical guard 56 is secured to the under side of the top 3 and is open at each end so that the air may freely pass. The fitting 5 is of course connected to the manifold of the engine by any suitable piping.

The gasoline is drawn into the chamber 2 through a fitting 4 provided with a strainer 26, a lock nut 25, a valve seat 28 and a valve 27, this latter being carried by a stem 14 which passes loosely through an operating lever 19.

The stem is provided with limiting nuts 35 15 and 16 through which it is caused to follow the movements of the lever 19 but is left free to seat properly on the seat 28 when the lever 19 moves it into the active path of the incoming gasoline.

40 The lever 19 is pivoted to a lug 18 on the top 3 and is formed with a shoulder 17 for limiting its movement in one direction. The long end of this lever 19 supports a cork float 6 which is pivotally connected to the lever by an adjusting screw 21 having a pivot head 20.

When the gasoline in the chamber 2 rises to its maximum level the cork 6 operates the lever 19 and draws the valve 27 close to its seat so that it receives the impact of the inwardly rushing gasoline and seats itself with a snapping action. This action is assisted by the valve being thus brought more closely under the influence of the vacuum in the chamber 2. The net result of the combined influences however is to cause the closing of the valve with a quick snapping ram like action.

60 After the valve closes as above described gasoline continues to pass up the air vent 7 until all the gasoline in the trap is exhausted when the air rushing up through this pipe relieves the vacuum in the chamber 2 and permits the gasoline to flow by gravity 65 from the chamber through the pipes 8 and 9.

The pipe 8 is provided at its lower end with a flat flap valve 42 held loosely in position by headed screws 43 so that it may move freely toward and away from its seat under the influence of the gasoline passing 70 in opposite directions. This valve is old and well known in the art and permits passage of the gasoline in one direction only.

The lower end of the pipe 7 is provided with an inverted shell 36 which together 75 with a standpipe 37 forms a feeding siphon for conducting the gasoline from the lower part of the tank 1 to the lower end of the pipe 7 and thus blocking this pipe against 80 the passage of air to the chamber 2 and causing the vacuum to be established or raised in the chamber and the pumping or raising of gasoline from the rear tank to be effected. The lower end of the pipe 37 is set in the sealed top of a shallow hollow disk 85 39. A standpipe 38 open at its top is similarly set in the top of the disk 39. When the gasoline passes down the standpipe 37 it fills the lower end of the standpipe and the hollow disk 39 and cuts off the air that might enter through the pipe 38 and thus causes solid gasoline to pass up through the pipe 7. After the trap is exhausted however and air passes under the lower end of the shell 36, sufficient gasoline is let down 95 from the chamber 2 to again seal the lower end of the shell and as air can break through the passage in the disk 39 and the lower end of the pipe 37 easier than through the shell 36 which is a dominant 100 lift, the shell 36 remains sealed while air passes through the pipe 38 and up the pipe 7 and permits the gasoline in the chamber 2 to descend until the siphon again pulls over and the operation is repeated.

105 The gasoline that flows down the pipe 9 and valve 42 at its lower end passes into the cup 40 and fills the same and overflows into the tank 1 to assist in raising the level for the operation of the siphon. This causes the 110 siphon to operate rapidly as it is fed through two pipes instead of one and the cup 40 is always kept full to give a constant head for the carburetor to which it is connected by a fitting 44 that also secures the cup 40 in 115 place in the bottom of the tank 1. The upwardly extending end 41 of this fitting traps sufficient gasoline in the cup 40 to keep the valve 42 covered and sealed at all times. The formation of the hollow disk 39 is such 120 that the pipe 7 clears of all gasoline as the air in passing from the pipe 38 to the pipe 37 presses down the gasoline in the disk 39 over an extended surface and any drops in the pipe 7 fall back on this extended surface 125 and do not restrict the passage of air as they would more or less if they fell back into a restricted pipe.

130 The pet cock 45 is provided for draining water and sediment from the tank 1.

If for any reason this tank should be depleted in its supply and the engine stop, the chamber 2 will always retain all the gasoline located below the upper end of the pipe 9 5 and this quantity will then descend and fill the siphon space and overflow into the empty cup 40. Upon restarting the engine there will be a supply for the carburetor and an extra large supply for the siphon, so that 10 the first pumping action will be a very long one which will carry the level of the gasoline up to the top of the pipe 9 and thus give sufficient head for the gasoline to again descend and fill the siphon. This head is 15 necessary as the passage of air through the restriction 31 at the top of the pipe 7 always leaves a slight vacuum in the chamber 2 which must be overcome. The gasoline after passing through the restriction 31 strikes the under side of an inverted cup 30 provided with an adjusting screw 29 which passes through the top 3. This cup causes the gasoline to be thrown back upon itself and thus tends to clog the upper end of the pipe 7 and offer 20 an additional resistance to the passage of the gasoline. This raises the vacuum in the chamber 2 more rapidly and to a greater extent and also throws the gasoline downward in an umbrella shaped spray that greatly 25 assists in saturating the air with fine particles of gasoline. The cup 30 serves the further purpose of closing the upper end of the pipe 7 when desired to cause the tank to pump gasoline without priming when it is first started or under any other conditions that might require priming.

In the modified form shown in Fig. 3 a movable obstruction for the upper end of the pipe 7 is shown. This consists of a valve 46 having a stem 48 and stops 49 and 50. The stem is mounted in an open yoke 51 which is secured to the upper end of the pipe 7. The valve seat 47 is also secured in the upper end of the pipe 7 and the valve 46 is provided with a weighted portion 52. When the gasoline passes up through the pipe 7 it strikes the valve and forces it toward its seat but the stop 50 striking the yoke 51 halts the valve before it is fully seated and leaves sufficient space for the gasoline to escape in reduced quantities. This results in raising the vacuum in the chamber 2 to a greater extent than if the valve were not present. When gasoline has all passed up the pipe 7, the air is not sufficient to support the valve and it falls back by its own weight until arrested by the stop 49 engaging the upper side of the yoke 51. When the valve is in this position the air can pass freely out of the upper end of the pipe 7 and the vacuum in the chamber 2 reduced as desired. It will be understood that a ball check valve may be used instead of the valve 46 if desired.

In order to give the tank 1 atmospheric pressure air vents 32 and 33 are formed in

the ring 54. Each of these vents is provided with a screw nipple 57, by means of which and suitable couplings 58, two pipes 13 and 34 respectively are attached.

The pipe 13 is coiled about the exhaust 70 pipe 12 of the engine and is open at one end. Hot air is thus supplied to the tank 2 to assist in vaporizing the gasoline and giving a more constant mixture to be fed to the engine through the suction pipe connecting the 75 tank to the engine manifold. The tank is also preferably located at some point in proximity to the engine so as to become heated thereby.

The pipe 34 is connected in any suitable 80 manner to the air space in the upper part of the radiator of the engine so that as the engine heats and hot vapors collect in this air space they will be drawn into the tank mixed with the gas laden air and fed to the 85 engine to assist in more perfect combustion and the elimination of carbon deposits. This is fed uniformly to the engine as the opening 55 is always open.

When the air pipe 7 clears the gasoline 90 starts to descend and the float 6 passes down with it relieving the valve 27 of any restraining influence and allowing it to open under the suction created by the gasoline in the pipe returning to the lower main tank as well 95 as under the influence of the weight of the float 6.

It will be seen from the foregoing that when the valve or cut off 27 closes no more gasoline can pass from the main tank to the 100 vacuum tank and all chance of overflow is thus eliminated whether it be from suction in the chamber 2 or gravity when the main tank occupies a position above the vacuum tank on a steep grade.

It will also be observed that the cup 40 and its valve 42 and pipe 9 might be eliminated when the tank is to be used in such engines as have a sustained vacuum which never falls below an operative point. The 110 tank will operate perfectly without these parts provided the vacuum never falls so low, even on wide open throttle, as to stop drawing gasoline from the main tank. I prefer to provide the tank however with 115 these protective features as many machines on wide open throttle practically reduce the vacuum to a point where the tank stops pumping and calls on its reserve to tide over that period. The reserve in the present tank 120 is the contents of the cup 40 and all the gasoline in the tank 2 above the upper end of the pipe 9. It will of course be understood that until the float 6 reaches its upper position that the tank continues to pump full 125 and complete operations or cycles limited only by the gasoline passing through the pipe 7 and that after it does approach its upper position it will only cause the valve to cut off the feed of gasoline for part of a 130

cycle. The tank under normal conditions operates with from six to eight cycles per minute pumping only the required quantity each time to replenish what had been used 5 since the previous cycle. Within certain limits the frequency of these cycles can be increased according to the quantity of gasoline passing through the trap and the head which it has in falling to the trap, so as to 10 secure what for all practical purposes is a continuous feed of gasoline from the main tank to the vacuum tank.

This continuous feed is of course the ideal feed as the vacuum tank is always full and as the trap is continually working and spraying gasoline to create the desired saturated mixture of air to be drawn to the engine.

It will be understood that while I have shown one form of carbureting device for the air vent pipe, that any other suitable form might be employed equally well, in fact that shown in Fig. 3 will also act in this way as when the liquid strikes against the yoke it will be sprayed to each side and the small amount passing the valve will assume the form of a spurting jet.

The connection of the tank to the radiator also provides against loss from the evaporation of the alcohol in winter use, as the radiator is sealed except for the pipe 34 and all the alcohol vapor is thus fed to the engine as a fuel.

It will further be seen that either one or the other of the pipes 13 and 34, or both may be omitted without affecting the practical operation of the tank but I prefer their employment as it renders the tank more efficient.

40 It will also be observed that the pipes 13 and 34 could be combined and one pipe led from the radiator, then about the exhaust pipe and finally to the tank. This would supply super-heated moist air to the tank
45 but in this event the usual form of air vent would left in the radiator as I do not wish to put an unrelieved pressure on the tank.

Having thus described my invention what I claim as new and desire to secure by Letters Patent is:

1. In a fuel feeding system the combination with an elevated tank having a vacuum chamber, of means discharging fuel from the chamber, a vacuum pipe connected to the chamber, a fuel supply pipe also connected to the chamber, a valve for this last connection seating to close in the direction of the inward flow of the fuel, and a float 55 for positioning the valve to bring it under the influence of the inwardly flowing fuel. 60

2. In a fuel feeding system the combination with an elevated tank having a vacuum chamber, of means discharging fuel from the chamber, a vacuum pipe connected to the chamber, a fuel supply pipe also con-

nected to the chamber, a valve for closing this last connection seating to close in the direction of the inward flow of the fuel, and a float controlling the valve to position it for action.

3. In a fuel feeding system the combination with an elevated tank having a vacuum chamber, of means discharging fuel from the chamber, a vacuum pipe connected to the chamber, a fuel supply pipe also connected to the chamber, a valve for closing this last mentioned connection moved to seat and close by the momentum of the inflowing fuel and the atmospheric pressure thereon, and means for moving the valve into and out of the sphere of influence of the inflowing fuel. 75 80

4. In a fuel feeding system the combination with an elevated tank having a vacuum chamber, of a vacuum pipe connected to the chamber, a fuel supply pipe also connected to the chamber, a supply chamber located to discharge into a trap chamber, connections from this supply chamber for the carburetor, a control or trap chamber located to discharge into the supply chamber, independent means discharging from the vacuum chamber into the supply chamber and into the control chamber, and an air vent for the vacuum chamber controlled from the trap chamber. 95

5. In a fuel feeding system the combination with an elevated tank having a vacuum chamber, of a vacuum pipe connected to the chamber, a fuel supply pipe also connected to the chamber, a trap chamber, an air vent for the vacuum chamber controlled from the trap chamber, means discharging fuel from the vacuum chamber into the trap chamber, an independent means discharging fuel into the trap chamber and also discharging fuel into connections for the carbureter, and connections for the carbureter. 100 105

6. In a fuel feeding system the combination with an elevated tank having a vacuum chamber, of a vacuum pipe connected to the chamber, a fuel supply pipe also connected to the chamber, a valve for closing this last mentioned connection moved to seat and close by the incoming force of the fuel, a counterbalancing float in the vacuum chamber for moving the valve into and away from the active influence of the incoming fuel, and means for connecting the tank to the carbureter. 110
115

7. In a fuel feeding system the combination with an elevated tank having a vacuum chamber, of a vacuum pipe connected to the chamber, a fuel supply pipe also connected to the chamber, a valve for closing this last mentioned connection moved to seat and close by the force of the incoming fuel, a lever connected to the valve and a float connected to the lever to counterbalance the valve and move it into and out of the sphere of the active influence of the incoming fuel. 13

8. In a fuel feeding system the combination with an elevated tank having a vacuum chamber, of a vacuum pipe connected to the chamber, a fuel supply pipe also connected to the chamber, a trap chamber, an air vent for the vacuum chamber controlled from the trap chamber, means connecting the vacuum and trap chambers, and an independent means for closing the air vent at will to cause the tank to pump independently of the trap.

9. In a fuel feeding system the combination with an elevated tank having a vacuum chamber, of a vacuum pipe connected to the chamber, a fuel supply pipe also connected to the chamber, an air vent for the chamber, a liquid seal for the air vent, means for feeding the fuel from the vacuum chamber, and means for closing the air vent at the will of the operator and independently of the liquid seal to cause the tank to pump independent of the regular operation of pumping.

10. In a fuel feeding system the combination with an elevated tank having a vacuum chamber, of a vacuum pipe connected to the chamber, a fuel supply pipe also connected to the chamber, a trap chamber, an air vent connecting the trap and vacuum chambers, means for spraying the gasoline as it issues from the air vent in the vacuum chamber, and means for connecting the tank to the carbureter.

11. In a fuel feeding system the combination with an elevated tank having a vacuum chamber, of a vacuum pipe connected to the chamber, a fuel supply pipe also connected to the chamber, a trap chamber, an air vent connecting the trap and vacuum chambers, a restriction in the air vent in the vacuum chamber, and means for connecting the tank to the carbureter.

12. In a fuel feeding system the combination with an elevated tank having a vacuum chamber, of a vacuum pipe connected to the chamber, a fuel supply pipe also connected to the chamber, a trap chamber, an air vent connecting the trap and vacuum chambers, fuel connection between the trap and vacuum chambers for causing continuous and complete pumping cycles and means in the vacuum chamber for preventing overflow of the same if the quantity of the fuel pumped exceeds the quantity discharged from the tank.

13. In a fuel feeding system the combination with an elevated tank for pumping the liquid fuel, of a vacuum pipe for connecting the tank to the engine, a fuel supply pipe also connected to the tank, means for supplying heated air to the tank, and means for connecting the tank to the carbureter.

14. In a fuel feeding system the combination with an elevated tank for pumping the liquid fuel, of a vacuum pipe for connecting the tank to the engine, a fuel supply pipe

also connected to the tank and an air supply pipe for the tank, arranged for connection to a heated portion of the engine.

15. In a fuel feeding system the combination with an elevated tank for pumping the liquid fuel, of a vacuum pipe for connecting the tank to the engine, a fuel supply pipe also connected to the tank, means for carbureting the fuel in the tank, means for supplying heated air to the tank and means for connecting the tank to the carbureter.

16. In a fuel feeding system the combination with an elevated tank for pumping the liquid fuel, of a vacuum pipe for connecting the tank to the engine, a fuel supply pipe also connected to the tank, and means for carbureting the fuel within the tank so that a combustible mixture will be formed in the tank and will be fed to the engine through the vacuum pipe.

17. In a fuel feeding system the combination with an engine having a water radiator connected thereto, of an elevated tank for pumping the liquid fuel, a vacuum pipe connecting the tank to the engine, a fuel supply pipe also connected to the tank, an air supply pipe for the tank attached to a heated part of the engine, and an independent air supply pipe for the tank connected to the air space of the radiator.

18. In a fuel feeding system the combination with an engine having a water radiator connected thereto, of a tank for pumping the liquid fuel, means for connecting the tank to the carbureter, a vacuum pipe for connecting the tank to the engine, a fuel supply pipe for the tank, and means connecting the tank to the engine and the radiator for introducing heated and moist air into the tank to be fed through the vacuum pipe to the engine.

19. In a fuel feeding system the combination with an engine having a water radiator connected thereto, of a tank for pumping the fuel, means for connecting the tank to the carbureter, a vacuum pipe for connecting the tank to the engine, a fuel supply pipe for the tank, and an air supply pipe for the tank connected to the air space of the radiator.

20. In a fuel feeding system the combination with a tank for pumping the fuel, of means for connecting the tank to the carbureter, a vacuum pipe for connecting the tank to the engine, a fuel supply pipe for the tank, and a guard open to the vacuum chamber at its opposite ends and closed at its sides for preventing the liquid fuel in the tank splashing up against the end of the vacuum pipe that enters the tank.

21. In a fuel feeding system the combination with an elevated tank having a vacuum chamber, of a vacuum pipe connected to the chamber, a fuel supply pipe also connected to the chamber, a trap chamber, an air vent for the vacuum chamber controlled from the

trap chamber, and an automatic restricting device operating in the air vent to obstruct the passage of liquid fuel but permit the free passage of air.

5 22. In a fuel feeding system the combination with an elevated tank for pumping the liquid fuel, of a vacuum pipe connected to the tank, a fuel supply pipe also connected to the engine, means for causing pumping 10 cycles in the tank, and devices cooperating

with said means for carbureting the liquid fuel in the tank so that it may be fed to the engine as a combustible mixture.

In testimony whereof I affix my signature in the presence of two witnesses.
